UNITED STATES PATENT OFFICE.

ROY C. BRETT, OF CLEVELAND HEIGHTS, OHIO, ASSIGNOR TO THE PURO WATER FILTER COMPANY, OF CLEVELAND, OHIO, A CORPORATION OF OHIO.

WATER COOLER FOR USE WITH REFRIGERATORS.

Application filed June 9, 1925. Serial No. 35,922.

The present invention relates to water cooling attachment for iceless refrigerators and the like, in which provision is made for the insertion of a water cooling receptacle in or adjacent to the refrigerating chamber of an iceless refrigerator, and in which provision is made whereby the water in the cooling system is maintained in constant circulation so as to prevent the water being cooled from freezing and thus rendering the cooling system useless until thawed out. By means of the present circulating system, not only is freezing of the water and closing of the system prevented, but also the possible bursting of the container and pipes. More particularly then, the present invention provides a cooling receptacle having an outlet connection for a spigot or faucet from which the cooled water may be withdrawn, and also providing two other connections to the receptacle both of which are connected separately to the water line so as to form a closed circuit through the cooling receptacle and allow the water in this closed circuit to continuously circulate and thus prevent freezing. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a vertical sectional view through a refrigerator showing in elevation one form of the present water cooling system as applied thereto; Fig. 2 is a view similar to Fig. 1 but showing the water cooling system in a modified form; Fig. 3 is a view similar to Fig. 1 but showing a different arrangement of the cooling system; Fig. 4 is a side elevational view of one of the cooling receptacles; Fig. 5 is an elevational view of the valve casing shown in Fig. 3 with part of the casing in section to show the valve operating mechanism; Fig. 6 is a fragmentary sectional view of a portion of the refrigerator showing a modified form of the construction shown in Fig. 3; and Fig. 7

is a plan view of one of the cooling coils, such as are used in the forms shown in Figs. 1 and 2.

In Figs. 1 and 2 the present invention is illustrated as being applied to icebox or refrigerator 1 having the usual several compartments, of which the compartment 2, shown as being in the upper right-hand corner, is that containing the usual iceless refrigerating unit 3 which is diagrammatically illustrated. In applying the present invention of a water cooling system to an icebox containing an iceless or electric refrigerating unit, I have used a cooling receptacle 5 which may be of any suitable type, this receptacle being in form shown in Figs. 1 and 2 a double receptacle, each portion thereof being connected to an outlet or withdrawal pipe 6 which has its outer end 7 extending through a suitable aperture 8 through the wall 9 of the refrigerator, and being provided with suitable faucet or spigot 10 on the outside of the refrigerator proper. Each of the two water cooling receptacles is connected through suitable unions or couplings 11 with a conduit, which, in the form shown in Fig. 1, are connected through a T coupling 12 to the main water line 14. In this form one of these pipes 13 extends upwardly through the refrigerating chamber and then horizontally adjacent the top thereof into the large compartment 15 and then downwardly to a point adjacent the bottom of the compartment near the side wall 16 thereof. The other pipe 13 extends downwardly through the chamber 17 under refrigerating compartment and then along the refrigerator, adjacent the bottom thereof to the T coupling 12.

In the form shown in Fig. 2 the two water cooling receptacles are connected to the outlet pipe 6 in the same manner as in the previous form but the inlet connections to the cooling receptacle are connected in a slightly different manner. The pipe 20 from the upper receptacle, as indicated in Fig. 2, extends up through the refrigerating compartment 2 and then laterally adjacent to the top of the refrigerator and out through an aperture 21 in the side wall 22 thereof. The pipe is then extended downwardly to the T coupling 12, which is lo-

cated outside of the refrigerator. The other pipe 23 from the lower receptacle extends downwardly, then laterally near the bottom of the refrigerator, out through an aperture 24 in the wall 22, and is then connected to the coupling 12, the coupling being connected to the main water line 14.

In this manner the water which is in the cooling system, consisting of pipes leading 10 to the two cooling receptacles and the receptacles themselves, circulates through the two pipes and the cooling receptacles in this interior closed system formed by the two pipes 13 or 20 and 23, the T coupling 12 and 15 the double receptacle 5. In the form shown in Fig. 2 a portion of this circulating cooling system is outside of the refrigerator proper and thus normally in a comparatively 20 warm zone, such as the ordinary kitchen room temperature, and this type of construction is used where the ice box temperatures are low and where extra heat is necessary to prevent the water from freezing in the cooling system.

25 In the form shown in Fig. 3 there is the usual ice-box structure, as shown in the previous figures, with a refrigerating unit 3 in its compartment 2 and in the water system shown in this figure, a single cooling receptacle 30 is used, which is connected through 30 a pipe 31 extending downwardly in the box, then laterally and running upwardly around the box to a T coupling 32 located near the top of the box, and then laterally to an operating valve and spigot casing 35 which 35 extends out through an aperture 36 in the box to provide the withdrawal faucet 37. This valve casing 35 is also directly connected through a pipe 34 to the other end 40 of the cooling receptacle 30. In this form, when the discharge spigot or faucet 35 is opened to draw cold water, the water would naturally flow directly from the T coupling 32 to the valve casing 35 from the main 45 water line 14 and would not pass through the cooling receptacle. To force the water to pass through the cooling receptacle and then out of the faucet or spigot 37, the valve casing (see Fig. 5) is constructed so as to 50 contain a second valve 38 which is mounted on the same valve stem 40 as the faucet valve 41 so as to close upon the opening of the withdrawal faucet valve 41, thus forcing the water to pass through the pipe 31 and the 55 cooling receptacle and then the pipe 34 to the valve 41 and faucet. This valve 38, however, is normally open in the closed portion of the faucet valve 41 and thus allows water in the system to circulate through 60 pipes and cooling receptacle to prevent freezing as in the forms previously described.

65 In Fig. 6 a slightly modified form of the device is shown, similar in general characteristics to the form shown in Fig. 3, but in this form the pipe 40 leading upwardly

from the single cooling receptacle is connected to the other pipe 42 from the cooling receptacle by means of a T coupling 43 and the faucet 44 is mounted on the other end of a nipple 45 mounted in the coupling 43 70 which extends out through the refrigerator wall. On the other pipe line 42 from the cooling receptacle is mounted an automatic valve 47 which is adapted to allow normal flow of water therethrough, such normal flow being that as will constantly occur in the closed system, but which will close under a greater than normal flow of water so as to prevent water from entering the T coupling from this line 46 which is close to the main water supply line and thus allow the water to be withdrawn from the faucet only through the other pipe and the cooling receptacle.

In the form shown in Fig. 1 the double 85 cooling receptacle is shown as being in the form of two cooling coils 50 and 51, which are best shown in Figs. 4 and 7. Each of these coils is formed of a double pipe wound into a spiral in the upper coil, as illustrated 90 in Fig. 7, having a union 52 at one end for connection to one of the water system pipes, while at the other end it is connected to a T joint 53 which is also connected to the other coil and to the withdrawal pipe of the system. It is, of course, obvious that any suitable water cooling receptacle may be employed and the form illustrated in Figs. 4 and 7 is a satisfactory cooling unit which 95 has been designed to operate in the present 100 type of cooling system.

105 It is desirable, under certain operating conditions, to provide an automatic heating device, as shown in Fig. 3, such heater being mounted on the lower part of the vertical section of pipe 31 in compartment 5. Such a unit consists of an electric heating coil or element 55 mounted adjacent the pipe 31 in an insulated box 56 and controlled by a thermostat 57. The thermostat is set 110 to close the switch to the heating device upon a predetermined temperature, this temperature in compartment 5 being such that the corresponding temperature at the cooling receptacle will be above that at which the 115 water in the circulating system will start to freeze. By the use of such a device, a predetermined temperature difference is maintained between the coil or cooling element and the portion of pipe 31, and this difference will be sufficient to force the desired 120 circulation of water through the system.

125 In all of the forms, a water cooling system is used which takes the form of a closed circuit including a cooling receptacle or chamber, one side of the circuit being connected to a water supply pipe and the other to a faucet. The water within the system may circulate freely but when the withdrawal faucet is opened water will flow 130

thereout, this water being forced to pass through at least one-half of the double cooling receptacle in the first forms or through the single receptacle in the other forms.

5 In addition, the modified forms are particularly adapted to meet certain operating conditions, such as a refrigerator where lower than ordinary temperatures are maintained, the system is simple in construction 10 and easy to install in any type of refrigerator.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a water cooling system, the combination of a refrigerator having a refrigerating chamber and another chamber, a water supply pipe, a cooling receptacle mounted in said refrigerating chamber, a cold water withdrawal pipe connected thereto, and two pipes connecting said cooling receptacle and said supply pipe and arranged to form a vertically arranged closed water circulation circuit, a part of such circuit being mounted in said other chamber to provide a temperature difference in said closed circuit for circulation purposes.

2. In a water cooling system, the combination of a refrigerator having a refrigerating chamber and another chamber, a water supply pipe, a closed water circulation circuit mounted in said refrigerator and including two pipes connected to said water supply pipe and to a cooling receptacle, said closed circuit being arranged vertically in said refrigerator and having a portion of said circuit in said refrigerating chamber and a portion of said circuit in said other chamber to obtain a temperature difference and circulation in the circuit itself, and a cold water withdrawal pipe connected to said cooling receptacle.

3. In a water cooling system, the combination of a refrigerator having a refrigerating chamber and another chamber, a water supply pipe, a closed water circulation circuit mounted in said refrigerator and including two pipes connected to said water supply pipe and to a double cooling receptacle, said closed circuit being arranged vertically in said refrigerator and having a portion thereof in the refrigerating chamber and a portion in said other chamber of higher temperature to obtain a temperature difference in portions of said circuit to obtain continuous circulation therein, and a cold water withdrawal pipe connected to the middle point of said double receptacle.

65 4. In a water cooling system, the combina-

tion of a refrigerator having a refrigerating chamber and another chamber, a water supply pipe, a closed water circulation circuit mounted within the refrigerator, said circuit including a double cooling receptacle mounted adjacent the refrigerating chamber and two pipes connected to the ends of said cooling receptacle and to said water supply pipe, said pipes extending vertically from said cooling receptacle and then into said other chamber of higher temperature than said refrigerating chamber to obtain circulation in said closed circuit, and a cold water withdrawal pipe connected to the middle point of said double cooling receptacle.

5. In a water cooling system the combination with a refrigerator of a water supply pipe, a double cooling receptacle in said refrigerator, a pipe connecting one of said cooling receptacle portions to said water pipe, a second pipe connecting the other portion of said receptacle to said water pipe, and a cold water withdrawal pipe connected to the middle point of said double cooling receptacle, one of said connecting pipes extending outside of the refrigerator and said two connecting pipes and said cooling receptacle forming a circulating circuit for the water in said system.

6. In a water cooling system for attachment to a refrigerator having a refrigerating chamber, the combination of a double cooling receptacle adapted to be mounted adjacent the refrigerating chamber, a water supply pipe, a pipe connecting one side of the cooling receptacle with said water supply pipe, a second pipe connecting the other side of said cooling receptacle with said water supply pipe, said two pipes and said cooling receptacle forming a circulation system for the water in said system, one of said connecting pipes extending outside of said refrigerator, and a cold water withdrawal pipe connected to the center of said cooling receptacle.

7. In a water cooling system for refrigerators, the combination of two cooling coils mounted adjacent the refrigerating means, a water supply pipe, a connecting pipe attached at one end to said water supply pipe and at the other to one of said cooling coils, a second connecting pipe attached at one end to said water supply pipe and at the other end to the other of said cooling coils, a pipe connection between said two coils, said pipes and cooling receptacle being arranged in a vertical plane to obtain a closed water circulating circuit and said pipes extending into portions of the refrigerator of higher temperature than the point adjacent the refrigerating means, and a water withdrawal pipe having a faucet connected to said pipe connection whereby water being withdrawn must pass through at least one of said cooling coils.

Signed by me, this 4th day of June, 1925.
ROY C. BRETT.
